CLAIM

The ornamental design for a computing device, as shown and described.

DESCRIPTION

FIG. 1 is a perspective view of a computing device showing our new design in a closed configuration;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the computing device of FIGS. 1-7 shown in an open configuration;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is the bottom view of FIG. 7 with an encircled portion enlarged in FIG. 16;

FIG. 16 is an enlarged view thereof, taken from encircled portion 16 in FIG. 15;

FIG. 17 is the bottom view of FIG. 14 with an encircled portion enlarged in FIG. 18; and,

FIG. 18 is an enlarged view thereof, taken from encircled portion 18 in FIG. 17.

The even-length broken lines in the drawings illustrate portions of the computing device that form no part of the claimed design. The dash-dot-dash broken lines in FIGS. 15, 16, 17 and 18 are included to show a partially enlarged view only and form no part of the claimed design.
